WATCH STAND

Richard P. Fleischner, Scarsdale, N. Y.

Application October 1, 1941, Serial No. 413,127

4 Claims. (CL. 248—117)

This invention relates generally to watch stands on which watches varying in size may be conveniently and securely supported. More particularly, it relates to watch stands in which provision is made for accommodating the attaching band of a wrist-watch, whereby wrist-watches may be mounted on the stand without removing the band from the watch.

The general object of my invention is the provision of a stand for watches that is attractive in appearance, effective and low in cost.

This object and such other objects as will hereinafter appear or be pointed out are attained in the illustrative embodiments of my invention shown in the drawing, in which:

Figure 1 is a perspective view of one illustrative embodiment of my invention indicating in broken lines watches of various sizes positioned thereon;

Figure 2 is a transverse section taken substantially on the plane indicated by the lines 2—2 of Figure 1, looking in the direction of the arrows, and showing in broken lines, a wrist-watch positioned on the stand;

Figure 3 is a sectional view similar to Figure 2, but showing other types of watches in place on the stand;

Figure 4 is a perspective view of a second embodiment of my invention;

Figure 5 is a sectional view in the plane indicated by the line 5—5 of Figure 4, looking in the direction of the arrows;

Figure 6 is an end elevational view, partly in section on the plane indicated by the line 6—6 of Figure 5, looking in the direction of the arrows; and

Figure 7 is a fragmentary perspective view, partly in section on the plane indicated by the line 7 of Figure 4, looking in the direction of the arrow.

Referring now to the drawing in detail, I have shown in Figure 1, a watch stand comprising a main or body portion 10 consisting of an inclined portion 11, which is supported at its rear by upright portion 12, and the body portion 10 is shown supported on a pair of foot portions 13 and 14 spaced from each other so as to provide a channel 15 between them. The outer surface of the inclined portion 11 is preferably slightly dished (see 16 in Figures 1 and 3). A pair of ribs 17 and 18 are shown arranged at the bottom of the inclined portion 11 on opposite sides thereof, and these may serve for the support of a watch, such as the watch indicated in broken lines by the numeral 19 in Figure 1 and 3. It will be observed that these ribs are concave and inclined, so that they will engage the lower lateral portions of a watch 19 and support it securely for ordinary purposes.

A second pair of ribs 20 and 21 are shown positioned one on each side of the inclined portion 11 but at a higher level, whereby they are particu-

larly adapted for supporting a watch somewhat smaller than the watch 19, which watch has been indicated in broken lines by the numeral 22 in Figures 1 and 3 at the midportion of the surface 11. The ribs 20 and 21 are in general similar to the ribs 17 and 18, but they may have a greater curvature in order to conform more closely to the peripheral portions of a watch 22, which is smaller than the watch 19.

10 A third pair of ribs 23 and 24 are shown on the inclined portion 11 at a higher level than the ribs 20 and 21, and are also spaced more closely together, whereby they are adapted for the support of a small watch such as the wrist-watch indicated in broken lines at 25 in Figures 1 and 2. These ribs are preferably curved still more than the ribs 20 and 21.

It will be observed that the respective pairs of ribs 17 and 18, 20 and 21, and 23 and 24 are spaced from each other, so as to leave a channel 25a between them along which may be led the strap 26 of a wrist-watch. The strap 26 may be led completely around the body portion 10 as appears from Figure 2, and if its ends are fastened together by the ordinary securing means, it will serve as a safeguard additional to the ribs 23 and 24 for holding the watch in place on the stand.

The convenience and adaptability of the stand shown in Figures 1, 2 and 3 will be apparent without further description. It is available at all times for watches of varying sizes, and is particularly convenient for wrist-watches of various sizes and shapes.

While the wrist-watch 25 has been shown positioned on the ribs 23 and 24, it will be understood that where the wrist-watch is different in size and contour from that shown at 25, that it may be supported on the other ribs.

It will be observed that the channels for accommodating the strap of a wrist-watch are so arranged that the watch will assume a position in which the 12 of its dial is uppermost, in other words, it assumes a normal position or reading position, rather than a sidewise or inverted position, or a random position which the watch might assume when laid on a table, and which it might have when picked up from the table.

The second embodiment of my invention shown in Figures 4 to 7 comprises a body in the form of 50 a block 30 having an inclined face 31, which has a circular depression 32 therein and a channel 33 on its under face. A short channeled portion 34 leads from the depression 32 into the channel 33. A pair of brackets 35 and 36 are shown pivotally mounted respectively at 37 and 38 on the block 30, whereby they are adjustable to various angular positions as indicated by the broken line 55 position of the brackets 35 and 36. Where the pivotal mounting 37 and 38 consists of a screw, 60 as shown, adjustment or locking thereof may

be effected by a tool such as a screw driver or a coin used as a screw driver. However, if it is desired to avoid the use of tools, obviously, manually manipulable mounting means may be used, such as a thumb screw or nut.

The brackets 35 and 36 may have a cross section as illustrated in Figure 7, in which the bracket 35 is shown as having a flat portion 35a and an inclined flange portion 35b, the latter being adapted to overhang the peripheral portion of a watch such as the watch shown in broken lines at 39 in Figures 4, 6 and 7. The bracket 36 also consists of similar parts 36a and 36b.

In the use of this embodiment of my invention a watch will be placed in the depressed portion 32 and the brackets 35 and 36 will then be adjusted to engage it at its side portions. In the case of a wrist-watch, such as that shown in broken lines at 39 in Figures 4, 6 and 7, its strap 40 will be led around the block 30 as indicated in Figure 6, its lower portion passing through the channel 33.

It will be observed that by making the brackets 35 and 36 of concavely curved contour and having portions of each disposed on opposite sides of its pivot, that when a watch is mounted between said brackets, and the watch is pressed downward against the lower portions of the brackets, the upper portions will move inwardly and press against the sides of the watch, whereby the lower portions will be held from spreading laterally and the watch will be held against downward movement.

As an added feature I may provide means for illuminating the watch carrying surface 31 of the stand. This feature obviously is particularly useful at night. It may consist of an incandescent bulb 41, suitably mounted as at 42 for effecting the desired illumination, and of energizing means therefor such as provided by a dry cell 43 which is conveniently mounted in a hollow in the base 30 within which it may be held by spring clips 44, or other suitable means. A suitable switching arrangement such as the push button 45 may be provided, whereby the circuit 46 of the bulb 41 may be closed if desired, this circuit of course being normally open.

While I have herein disclosed several illustrative embodiments of my invention it will be understood that the same may be embodied in many other forms without departing from the spirit thereof, as will be obvious to those skilled in the art. It will be further understood that the disclosure herein is by way of illustration merely, and is not to be construed in a limiting sense, and that I do not limit myself, other than as called for by the prior art.

Having thus described my invention and illustrated its uses, what I claim as new and desire to secure by Letters Patent, is:

1. A stand for watches comprising a support having an inclined surface on which the back of the watch may rest and means pivotally mounted on said support adapted to engage the opposite sides of a watch positioned on said inclined surface, said means limiting lateral and downward movement of the watch, and having portions on opposite sides of their points of pivoting, so disposed that when the watch moves against the portions on one side of said pivot, the portions on the opposite side of said pivot will be pressed against the watch.

2. A stand comprising a support having an inclined surface on which the back of the watch

may rest, and curved means pivotally mounted on said support and having its concave side adapted to engage the opposite sides of a watch positioned on said inclined surface, said means limiting lateral and downward movement of the watch, and having portions on opposite sides of their points of pivoting, so disposed that when the watch moves against the portions on one side of said pivot, the portions on the opposite side of said pivot will be pressed against the watch.

3. A stand for a watch to be positioned on a night table or the like, said stand presenting a top surface upon which a watch is to be received, said surface being at an angle so that the dial face of the watch can be read conveniently by a person in bed or in a reclining position, and means on said surface for engaging and supporting the watch in predetermined position on said surface and against downward sliding movement, said means comprising spaced abutment elements positioned to the opposite sides of the central vertical plane longitudinally through the stand, said elements extending generally from a lower point on the stand to a point thereabove and presenting inner curved surfaces for watch rim engagement, said elements being spaced apart at their lowermost points a sufficient distance to permit the strap of the watch to be passed therethrough, and the curvature of the aforementioned inner surfaces being such that it will approximate that of the rim of the watch, the upper ends of the abutment element being spaced apart a sufficient distance to permit the watch to be received therebetween so as to be free to gravitate downwardly into engagement with the curved inner surfaces of said elements and into abutting supporting relation to the lower ends thereof.

4. A stand for a watch to be positioned on a night table or the like, said stand presenting a top surface upon which a watch is to be received, said surface being at an angle so that the dial face of the watch can be read conveniently by a person in bed or in a reclining position, and means on said surface for engaging and supporting the watch in predetermined position on said surface and against downward sliding movement, said means comprising spaced abutment elements positioned to the opposite sides of the central vertical plane longitudinally through the stand, said elements extending generally from a lower point on the stand to a point thereabove and presenting inner curved surfaces for watch rim engagement, said elements being spaced apart at their lowermost points a sufficient distance to permit the strap of the watch to be passed therethrough but not sufficient to permit an average size watch to pass therethrough, and the curvature of the aforementioned inner surfaces being such that it will approximate that of the rim of the watch, the upper ends of the abutment element being spaced apart a sufficient distance to permit the watch to be received therebetween so as to be free to gravitate downwardly into engagement with the curved inner surfaces of said elements and into abutting supporting relation to the lower ends thereof said elements being so arranged and constructed as to accommodate watches varying as to diameter and thickness within a predetermined range of such variations.
